UNITED STATES PATENT OFFICE.

JOHN POWELL AND FRANK EVANS, OF FERRIDAY, LOUISIANA.

LOG HOIST.

Application filed September 12, 1923. Serial No. 662,300.

To all whom it may concern:

Be it known that we, JOHN POWELL and FRANK EVANS, citizens of the United States, residing at Ferriday, in the parish of Concordia and State of Louisiana, have invented certain new and useful Improvements in Log Hoists; and we do hereby declare the following to be a full, clear, and exact description of the invention, such as will enable others skilled in the art to which it appertains, to make and use the same.

The present invention relates to improvements in log hoists and consists in the constructions, combinations and arrangements herein described and claimed.

Objects of the invention are to improve hoists for the raising of logs in which ease in handling great quantities of logs will result at an expenditure of a small amount of labor, in providing a machine which will not be apt to get out of order and which will enjoy an unusual freedom from repairs.

In the drawings, wherein like symbols refer to like or corresponding parts throughout the several views:—

Figure 1 is a top plan view of the log hoist constructed according to the present invention.

Figure 2 is a side view thereof.

Figure 3 is a plan view on an enlarged scale of the tongs or grapple.

Figure 4 is a side view of the same with the jaws in the initial position, and

Figure 5 is a similar view showing the jaws or hooks extended.

Referring more particularly to the drawings 6 designates generally a foundation upon which the device is erected and 7 designates a turn table mounted for rotary movement on the base 6 and having rollers 8 to support it for this rotary movement.

A mast 9 is supported eccentrically upon the turn table 7 and at preferably a slight backward inclination and a boom 10 is pivotally supported as at 11 near the base of the mast. The boom 10 extends outwardly diagonally and is provided with guide grooves 12 along its sides into which portions of a carriage 13 extends and are guided in the longitudinal movement of the carriage along the boom.

The boom is adapted to be raised and lowered and the carriage to be adjusted along the boom and the carriage supports the tongs or grapple and appropriate means is provided for the raising and lowering of

the tongs and grapple and for opening and closing the grapple hooks or jaws. Of course the mast 9 will be supported by suitable guy wires and there may be a connection between the top of the mast and the top of the boom for restricting the downward swinging movement of the boom but these guy wires and connections are not illustrated as the same would interfere with a proper illustration of the other features of the device.

Upon the rotary platform 7 are a number of drums 14, 15, 16, 16', 17 and 18, these drums being supported for rotary movement in an appropriate frame 19, and having cranks 20 by which they may be manually rotated to wind or slacken the cables which are engaged about the same. The drums will be provided with ratchet mechanism 75 to hold same against rotation. Now the uppermost drum 14 is provided with the cable 21 which extends upwardly through a guide arm 22 extending from a guide collar 23 which surrounds and which is affixed to the mast 9. The cable 21 extends up to the top of the mast and over idlers 24 by which it is directed substantially horizontally along to the outer end of the boom 10 which is also provided with idlers 25 at its corner portions in order to guide the cable about the under side of the boom. The free end of the cable is affixed in an eye or other fastening 26 carried by the upper end of the carriage 13. By winding the cable 21 upon the drum 14 the carriage 13 is raised or pulled outwardly upon the boom 10.

A second drum 15 is wound with a cable 27 also passing up through an eye in the guide arm 22 to the intermediate point upon the mast 9 where it is directed horizontally by means of the double pairs of guide rollers 28 and 29 to the opposite side of said mast where it is continued upwardly 100 in substantial parallelism with the mast to an idler 30 about which it is trained, being thence carried horizontally or substantially so to a similar idler 31 affixed near the outer end of the boom 10 and to the upper side thereof. The cable is returned upon itself and passed beneath the horizontal run to an eye 32 upon the bracket of the idler 30. By winding the cable 27 upon the drum 15 the boom 10 is raised 105 angularly as required.

Taking up the next drums 16 and 16'

which are half drums or divided drums on the same plane, these are provided with a pair of cables 33 and 34 shown best in Figure 1, these cables being wound in reverse directions upon the drums so that the rotation of one drum will act to wind and unwind one cable and the rotation of the other drum to tighten and slacken the other cable.

These cables 33 and 34 extend up to and through a pair of eyelets 35 carried by a collar 36 clamped upon the mast 9 beneath the collar 23, the eyes 35 being upon opposite sides of the mast as shown in Figure 1 for drawing the cables to opposite sides of said mast and to the eyelets 37 carried upon opposite sides of the boom 10 near its lower end. From this point the cables 33 and 34 diverge to the outer ends of the tongs or grapple frame to which they are affixed as indicated at 38 and 39. By turning the drums 16 and 16' in one direction the tongs or grapple frame may be rotated in a horizontal plane and by reversing the direction of rotation of the drums 16 and 16' a corresponding reversal in the direction of rotation of the tongs or grapple frame may be effected.

The drum 17 is provided with the cable 40 extending through a slot in the mast as indicated at 41 or through a slot in a guide secured to the mast. The cable 40 extends up in parallelism with the under side of the boom 10 to and about a guide roller 42 mounted in the carriage 13. The cable is thence directed downwardly to an eye or ring 43 to which a pair of branch cables 44 and 45 are attached diverging from the ring to opposite ends of the tongs and being passed respectively through idlers 46 and 47, having their lower runs extending toward one another or centrally and being affixed to movable blocks 48 and 49 to which the substantially semicircular grapple hooks 50 and 51 are attached as by central pivoting at 52 and 53. The lower ends of the semicircular hooks are sharpened or pointed for engagement with the ends of the log or the like, while the upper ends of the hooks are provided with eyes to receive the lower ends of the branch cables 54 and 55 being secured in common at their upper ends to the ring 56 suspended from the idler pulley frame 57. This idler frame carries the pulley 58 through which is reaved a cable 59. The free end of the cable 59 is affixed to the eye 60 carried by the lower intermediate part of the carriage 13. The cable also runs over the idler 61 carried by the lower end of the carriage 13 and from this point the cable 59 extends along parallel with the cable 40 and to and through a slot 62 made in the base of the mast or a guide secured to the mast, said cable 59 being wound about the drum 18 last in line.

In operation the tongs or grapples are

brought to an appropriate position for engaging the log by the pivotal movement of the boom 10 which is accomplished as above described by the winding or unwinding of the cable 27 in relation to the drum 15 and 70 furthermore by the adjustment of the carriage 13 upon the boom 10 which is achieved as heretofore described by use of the cable 21 in connection with its drum 14. In accordance with the disposition of the log to 75 be lifted, the grapple drum must be turned more or less in one direction or another for the purpose of bringing the grapple hooks into position to engage such ends of the logs and for this purpose the intermediate drums 80 16 and 16' are rotated in the one or other direction. The grapple frame is then lowered by unwinding both the drums 17 and 18 and the hooks 50 and 51 are separated by this same movement. In grappling a log the 85 cable 59 is wound upon the drum 18 which draws the two hooks together upon the log at the same time tends to lift the log together with the frame. The other drum 17 is moved to slack its cable. The boom may be then swung by rotating the turn table while the log is held elevated until the destination of the log is reached whereupon the cable 59 is slackened off the drum and the cable 40 is wound so as to draw the grapple 90 hooks 50 and 51 apart.

With the construction as described it will be apparent that grapple frames may be made to undergo a great variety of movement necessary to bring the same quickly 100 into a most convenient position for engaging the log and that the log may be delivered quickly to its destination, there released the mechanism restored without delay for the lifting and transporting of subsequent logs. The machine will act to both load and unload the logs or other similar articles.

It is obvious that various changes and modifications may be made in the details of 110 construction and design of the above specifically described embodiment of this invention without departing from the spirit thereof, such changes and modifications being restricted only by the scope of the following 115 claims:

What is claimed is:—

1. A grapple construction comprising a slotted frame, blocks slidably mounted in the slot in the frame, means for simultaneously drawing the blocks away from one another, hooks pivoted at an intermediate point to the movable blocks, and means attached to the upper portions of the hooks for releasing the hooks and at the same time drawing the blocks toward one another.

2. A grapple construction comprising a frame having fixed end pieces and separated side bars, blocks fitted to slide longitudinally on said side bars toward and from the end 120

pieces, means associated with the end pieces for drawing the blocks outwardly toward said end pieces, a pair of hooks of semicircular form pivoted at substantially their central portions to the inner edges of the blocks and adapted to swing toward and away from one another, the lower ends of said hooks adapted to grasp a log, and means coupled in

common to the upper ends of said hooks and at the same time rocking the hooks about their pivoted point on the blocks to withdraw the lower ends from the log and to pull the blocks inwardly toward the center of the frame. 10

JOHN POWELL.
FRANK EVANS.
